(57) CLAIM

The ornamental design for cosmetic product with quilted pattern as shown and described.

DESCRIPTION

1. Cosmetic product with quilted pattern

1.0 : Top view of cosmetic product with quilted pattern
The sole FIGURE is a plan view of a cosmetic product with a quilted pattern element of our new design shown in an environment of use. Portions of the cosmetic product shown in dash-dash broken lines form no part of the claimed design. The rectangular dot-dash broken line perimeter depicts the boundaries of the claimed design and forms no part thereof.

1 Claim, 1 Drawing Sheet
